UNITED STATES PATENT OFFICE.

FRED WEINDEL, JR., OF ALLENTOWN, PENNSYLVANIA, ASSIGNOR TO L. F. GRAMMES & SONS, INC., OF ALLENTOWN, PENNSYLVANIA, A CORPORATION OF MARYLAND.

UTILITY BOX.

Application filed August 25, 1926. Serial No. 131,334.

This invention relates to containers or boxes,—more particularly to the ornamental type with hinged lids ordinarily known as "utility boxes" adaptable for use as jewelry cases, candy boxes, humidors, etc.

In connection with boxes of the kind referred to, I aim to simulate the appearance of sturdy metallic construction without actual sole use of metal in their fabrication thereby to render them extremely light yet amply durable for the uses intended. This end I attain by employing for the body of the box, a foundation frame fashioned from suitable light weight material such as wood, fibre or composition, lining the interior with fabric or very thin metal (depending upon the use for which the box is ultimately intended), and sheathing the frame sides exteriorly with comparatively heavier sheet metal, as well as by constructing the lid for the box along generally similar lines. The invention is characterized by the simplicity and effectiveness of the means by which the various elements of the composite box are held together in their proper relationship.

Further objects of my invention are to secure in a box constructed as outlined, air and moisture tightness not only in the box proper, but along the meeting plane between the latter and the lid; and in general, to provide a utility box that is ornate, highly attractive, and conducive to very economical manufacture.

In the drawings herewith, Fig. I is a perspective view of my improved utility box.

Fig. II is a longitudinal sectional view of the same.

Fig. III is a transverse section designated by the arrows III—III in Fig. II; and

Fig. IV is a fragmentary detail sectional view showing the construction at the box corners.

With more detailed reference to these illustrations, 5 indicates the foundation frame for the box proper herein generally designated by the letter B and shown as of rectangular configuration, said frame being constructed preferably from comparatively light weight material such for example, as wood or fibre, with the sides 6, 7, 8 and 9 and the bottom 10 dove tailed or nailed together, or from composition molded to the desired form,—all as desired or found most convenient in practice. This foundation frame 5 I first line interiorly with sheet material 11 which may be

either fabric—like plush for jewelry cases—or very thin metal such as tin for candy boxes. In either case, the margins of the lining 11 are brought over the exposed top edges of the foundation frame 5 to envelop the same and 60 partially overlap the sides 6, 7, 8 and 9 at the exterior as shown at 12—12 in Figs. II and III. I next apply the outside metal sheathing which may be either in one piece bent to rectangular shape; or may consist 65 of separate plates 13. In the latter event, I preferably employ corner angle pieces 14 to overlap contiguous edges of the sheathing plates 13 and secure the several parts together by fastening means such as nails or 70 screws shown at 15, see Fig. IV more particularly. It will be especially noted from the drawings that the width of the sheathing plates 13 corresponds to that of the frame sides 6—9 so that the lapping areas 12 of the 75 interior lining 11 are concealed upon completion of the box. When fabric is used for the lining, the same is preferably secured by gluing. With a lining of sheet metal, tacks 16 (Figs. II and III) through the lapping 80 areas into the frame 5 may be relied upon as a convenient means to prevent subsequent displacement of such lining. It will be apparent, however, that the exterior sheathing 13 is capable of holding the inner lining 11 in 85 place without the use of additional fastening means such as the tacks 16. In like manner the corner angles 14 are adapted to hold the exterior sheathing 13 firmly against the frame. Thus, in effect, the corner pieces 14 90 are functional to hold both the inner and outer coverings in place, and the only visible fastening means are the nails 15 which pierce the corner pieces. When the box is intended for use as a humidor for cigars or cigarettes, 95 the foundation frame 5 may be constructed from cedar wood or other material having preservative qualities, and left unlined interiorly.

In constructing the box lid L, I employ a 100 foundation board 20, which, like the foundation frame 5, may be of wood fibre or composition; and for the purposes of ornamentation, said board is preferably beveled along the edges as shown and made to dimensions 105 determining a certain amount of overlap beyond the confines of the box proper B. With the foundation board suitably prepared as described, I apply a covering 21 to its lower face of material corresponding to the lining 110

used in the box proper B, allowing ample marginal projection to envelop the board edges and partially overlap the top face thereof as at 22—22. An outer covering 23 of sheet metal is thereupon applied to the foundation board 20 and its margins bent around the board edges as at 24—24 to overlap, and thus assist retainment of the under covering 21. As herein shown, the lid L is secured to the box proper B by suitable hinges such as shown at 25, the same being recessed into the back 6 of the frame 5 to allow direct contact of said lid with the top perimetric edge of the box proper; and suitable means, for example, a hasp 26 and eye 27, may be used to fasten down the free edge of the lid. With a foundation frame 5 and foundation board 20 of the proportionate thicknesses shown, the completed box resembles one of heavy and massive construction and is highly pleasing to the eye, though very light in actual weight. In practice, the ornamental appearance may be heightened by figurative designs, etched or otherwise impressed on the external sheathing, symbolizing the use for which the box is intended.

While I have herein referred to my invention as a utility box, it will be apparent that the novel structural features may be embodied, with advantages equal to those pointed out, in boxes or containers for other purposes.

As an alternative in the method of construction, I may apply the lining material sepa-

rately to the sides 6, 7, 8, 9 and bottom 10 preparatory to incorporation of these parts into the foundation frame, thereby greatly facilitating assembling in some instances at a substantial saving in labor costs.

Having thus described my invention, I claim:

1. A box of the character described comprising a frame, an inner lining of sheet metal with margins enveloping the exposed edges and partially overlapping the outer sides of said frame, an exterior sheathing of metal concealing the lapping areas of the inner lining, corner angles overlapping the contiguous edges of the exterior sheathing, and fastening means through said corner angles whereby said corner angles are effective to hold the exterior sheathing and inner lining firmly in place without the employment of additional fastening means.

2. A box of the character described, comprising a frame having side walls, a bottom and a lid, an inner lining of sheet metal with margins overlapping the exposed frame edges of the sides and lid, an exterior sheathing of metal concealing the overlapped areas of the inner lining and partially overlapping the bottom face covering of the lid at its edges, and corner angles for holding the side sheathing in place.

In testimony whereof, I have hereunto signed my name at Allentown, Pennsylvania, this nineteenth day of August, 1926.

FRED WEINDEL, JR.
